MERRITT C. ROSE, BERT R. ROSE, AND HENRY L. ROSE, OF PARMA, IDAHO

SORTER

Application filed December 11, 1928. Serial No. 325,240.

This invention relates to improvements in sorters, or sorting tables as they are sometimes termed, and consists of the constructions, combinations and arrangements herein described and claimed.

An object of the invention is to provide a sorter in which certain so-called eliminating belts are made to perform the double purpose of discarding objects of an objectionably small size and conveying the remaining but larger objects to the grading rolls by which such objects are continuously turned so that an inspector can cast out the defective objects and permit the others to pass on.

Another object of the invention is to provide a certain elevating rod which both supports a chute beneath the eliminating belts and is so disposed crosswise of the belts as to raise objects protruding through perforations in the belts, causing such objects to pass on to the grading rolls and preventing sticking and clogging of the belt mechanism.

A further object of the invention is to adapt the sorter to the purpose of sorting fruit, apples being herein specified merely for the purpose of stating one particular use of the device.

Other objects and advantages appear in the following specification, reference being had to the accompanying drawings in which:

Figure 1 is a perspective view of the improved sorter.

Figure 2 is a detail plan view, particularly of the eliminating device.

Figure 3 is a detail longitudinal section taken on the line 3—3 of Figure 2.

Figure 4 is a cross section of the upper bearing block taken on the line 4—4 of Figure 3.

Figure 5 is a section on the line 5—5 of Figure 3.

Figure 6 is a section on the line 6—6 of Figure 3.

Figure 7 is a section on the line 7—7 of Figure 3.

Figure 8 is a detail side elevation of a portion of the eliminating device as viewed in the opposite direction from Figures 1 and 3, particularly showing the idler drive and one of the swinging boxes.

Figure 9 is a detail section taken substantially on the line 9—9 of Figure 1.

Figure 10 is a cross section of the lower bearing block taken substantially on the line 10—10 of Figure 9.

It has been previously indicated that the sorter is intended for the particular purpose of sorting apples, but that this purpose is merely illustrative and is not to be construed as a restriction on the use of the invention. It may be used in the sorting of agricultural products other than apples, and it is even conceivable that the principles of the invention may be employed for the sorting of other objects.

As an apple sorter, the invention has a number of advantageous features. One of these features resides in the so-called eliminating device. This device includes perforated belts which convey the apples from the loading hopper to the grading rolls. In so conveying the apples, those that are objectionably small will be discarded at the beginning by virtue of falling through the perforations.

According to this principle, it is only necessary to regulate the size of the perforations in order to secure any desired preliminary separation of the apples. For example, perforations larger than those herein contemplated would cause the discarding of all but the very largest apples. By having the objectionably small fruit cast out in the beginning, the operatives will be concerned only with looking for bruised or other defective fruit.

Another novel arrangement resides in a so-called rod which prevents the sticking of the apples in the perforations of the eliminating belts. This rod is so located that such apples will be pushed up and out of the perforations, thus avoiding the likelihood of jamming. There are other novel features in the device, but these will be developed as the description proceeds.

Attention is directed to the drawings. A frame-work, generally designated 1, comprises legs 2, a set of longitudinal and parallel stiles 3, upper and lower heads 4 and 5 (Figures 3 and 9), an arrangement of brac-

ing of which all elements are designated 6, and a base frame 7 which has uprights 8. The base frame is defined in part by an adjacent brace 6 of the framework (Figure 1), and it is between this brace and base frame that a base 9 for a motor 10 is supported. This motor turns a drive wheel 11 by means of a belt 12.

For the purpose of distinction, that end 10 of the sorter at the right of Figure 1 is herein known as the upper end, while the end at the left is known as the lower end. The upper legs 2 have brackets 13 (Figures 1, 3 and 8) fixedly secured thereto at 14 in order to firmly 15 support the eliminating device. This device has outside stiles 15 and a central partition 16. The stiles and partition carry guides 17 in which the edges of a pair of belts 18 ride along the upper sides of the belts.

20 These belts are perforated at 19 (Figs. 2 and 3) for two purposes, one to let objectionably small apples drop through to the small apple chute 20, (Fig. 7), two to pick up and convey fruit of a desired size up to the guards 21 and onto the grading rolls 22. A pair of primary chutes 23 (Fig. 7) receives the small apples from the belts 18. These slope toward the center of the eliminating device where they have a common outlet at the 30 point 24. The ends of the chutes confront each other adjacent to this point. The chute 20 is disposed under the chutes 23, and receives the apples discharged at the point 24. The chute 20 slopes to one side of the sorter 35 and at the resulting deep end has a slidable gate 25. This gate is closed when the attendant has other duties to perform, and is opened to let the accumulated apples out.

An angle iron 26 (Fig. 3) extending 40 across the upper end of the sorter supports adjacent edges of the primary chutes 23. A rod 27, also extending crosswise but of the upper end of the sorter, supports other but also adjacent edges of the chutes 23. The 45 angle iron and rod are located inside of the belts 18. They occur at opposite extremities of the primary chutes and support the primary chutes in the sag of the belts as plainly shown in Figures 3 and 7.

50 The rod 27 is herein known as the elevating rod. Although the adjacent edges of the primary chutes 23 are curled over the elevating rod, it is actually the position of the elevating rod in reference to the upper sides 55 of the belts 18 that enables those apples sticking in the perforations 19 to be pushed out before such apples can reach the drive roll 28. By pushing the apples out the elevating rod 27 prevents any possibility of the 60 apples being crushed between the inside of the belts and the adjacent right side of the drive roll 28. This would set up an objectionable condition in the sorter. But the elevating rod prevents this and performs 65 what is regarded a very important function.

Briefly reverting to the perforations 19, these may be arranged in any desired manner. It is probably preferable to arrange them in rows as shown in Fig. 2. The size of the perforations can be fixed to meet particular 70 demands. That is to say, a set of belts 18 would have perforations of one size to discard apples of a particular small size but carry over apples larger than the particular perforations. Another set of belts might 75 have perforations either larger or smaller.

A tightener roll 29 bears against the undersides of the belts 18 in the direction of the drive roll 28 (Fig. 3). The two rolls are driven together by spur gears 30 fixed on one end of each of the rolls (Fig. 8). The shaft 31 of the tightener roll 29 is carried by boxes 32 (see Fig. 8) supported by arms 33 which are pivotally attached at 34 to the brackets 13. Bolts 35, carried by the brackets 13, extend through openings in the arms 33 and carry springs 36 which are adjustable as to tension by nuts 37 on the extremities of the bolts. The effect of the springs is to hold the tightener roll 29 up against the belts as previously stated and as shown in Fig. 3.

An idler roll 38 (Fig. 3) completes the supports of the belts 18. This roll is suitably journaled upon the outside stiles 15 of the eliminating device, or in such an other manner as best practice may dictate. The idler roll adjoins a loading hopper 39. This hopper can be supported by the outside stiles 15. It comprises nothing more than a flanged tray into which the apples are dumped and from which they are taken up by the perforated belts 18 of the eliminating device.

That end of the shaft 40 of the drive roll 28 opposite to the end by which one of the gears 30 is carried has a sprocket 41 (Figs. 1 and 2) to which a chain 42 is applied. The chain is also applied to a drive sprocket 43 on one end of a counter shaft 44 (Figs. 1 and 6). The opposite end of the shaft carries a bevel gear 45 which meshes with and is driven by a similar bevel gear on the shaft 46 of the drive wheel 11 already mentioned. The counter shaft 44 is suitably journaled at 47 upon the base frame 7.

A cross shaft 48 (Figs. 1 and 6) carries sprockets 49 and 50. The first of these is driven by a chain 51 from a sprocket 52 on the shaft 46. The second of these is to be regarded as one of a train of sprockets the other members of which are designated 53 in Fig. 6. These members are affixed to the exposed ends of stub shafts 54 (Fig. 3) driven into the upper ends of the grading rolls 22. Similar stub shafts 55 (Fig. 9) are driven into the lower ends of the grading rolls.

A sprocket chain 56 (Fig. 6) is the common driver for all of the grading roll sprockets 53. Obviously the chain is continuous. In addition to its application to the sprocket train it runs over idler pulleys 57 which are

so placed as to properly direct the chain and to hold the various components thereof against the members 53. The idler pulleys include an adjustable pulley 58 (Fig. 6). 5 This pulley is carried by an angle iron 59 which is slotted in its base portion to receive bolts 60 (Fig. 1) by which the angle iron is affixed to one of the outer stiles 3 of the framework. 10 By adjusting the angle iron 59 up and down the chain 56 can be tightened or loosened. The pulley 58 thus becomes a chain tightener. It is observed in Fig. 6 that the common drive chain 56 runs 15 along the underside of one set of sprockets 53 and the upper side of the second set. The corresponding sets of grading rolls 22 are thus driven in opposite directions. This turning is toward the longitudinal center of 20 the sorter.

It is along the longitudinal center of the sorter that a cull chute 61 is located. This cull chute appears between the adjacent and central longitudinal stiles 3. The cull chute 25 slopes toward the lower end of the sorter where it discharges into a cull box 62. This box, like the small apple chute 20 in Fig. 7, slopes to one side (in this instance the opposite side) of the sorter. The deep end of 30 the cull box has a gate 63 which can be opened and closed for obvious purposes.

In practice the grading rolls 22 will be given a slight pitch of approximately 6 inches in six feet of length. The slope will 35 be toward the lower end of the sorter where the discharge of the inspected fruit occurs upon an offtake table 64. The grading rolls are spirally wound with ropes 65. The apples follow the trough between the rolls, and 40 the combined action of the rolls and ropes is to continuously keep the apples turning so that any imperfections may be perceived by the operatives seated beside the sorter. Defective apples will be picked out by the operatives and thrown into the cull chute 61 while 45 the good apples will be permitted to move down upon the offtake table 64.

The upper and lower heads 4 and 5 (Figs. 50 3 and 9) may comprise angle irons in which bearing bars 66 and 67 are appropriately seated. These bearing bars are composed of hickory or other hard wood. They are bored with sets of holes 68 (Figs. 4 and 10) 55 by which the stub shafts 54 and 55 are received and in which these shafts have their principal bearing. Fine ducts 69 bored perpendicularly to the holes 68 and communicating therewith permit oiling. The extremities of the grading rolls 22 are bound with steel or other bands 70. The purpose of the bands is to keep the rolls from splitting particularly when the stub shafts are driven in. The bands also serve the purpose of holding 60 the ends of the rolls in such a compressed

state that the split shafts cannot work out nor turn within the rolls.

The operation is readily understood. The operatives will be located at each side of the sorter in Fig. 1 and watch the apples as they move along the grading rolls 22 from the upper right hand of the sorter to the lower left end. The grading rolls are divided into two sets by the central cull chute 61, and one or more operatives will stand beside each of the sets of rolls. 70

As the apples are revolved by the action of the grading rolls, and moved toward the lower end of the sorter by the spiral ropes 65, any imperfections will be seen. The undesirable apples will be picked out and thrown into the cull chute from which they are discharged into the cull box 62. The good apples are permitted to discharge upon the offtake table 64. 75

A supply of apples is dumped upon the loading hopper 39. The eliminating device aids the operatives in making a preliminary separation of undesirable apples from good apples. As the apples are initially picked up by the perforations 19 in the belts 18 they will be conveyed over the primary chutes 23 (Fig. 7) which are located in the sag of the belts as shown in Fig. 3. Apples smaller than the perforations will drop through and be discharged into the chute 20, (Fig. 7). The other apples will be conveyed on to the grading rolls. 80

The elevating rod 27 is so located beneath the upper sides of the belts 18 that the protruding portions of the apples will be pushed up and out before the drive roll 28 is reached. For example, the apple *a* in Fig. 3 will be pushed out when it reaches the rod 27. Were it not for the rod, it might be possible for the apple to stick in the perforation so tightly that the protruding portion would be crushed between the belt and the drive roll 28. This would set up an objectionable condition. The eliminating device might become 95 jammed. 100

The manner in which the tightener roll 29 is mounted and operated is easily understood. The arms 33 by which the bearing boxes of this roll are carried are capable of swinging on the arc of a circle of which the pivot 34 comprises the center. The tightener roll 29 will thus always be held well under the belts as shown in Fig. 3. There is no likelihood of the roll 29 ever slipping off and out of 105 place. 110

As the apples are discharged from the eliminating device they pass over the guards 21. These guards cover the sprocket train 53 in Fig. 6. They prevent dirt, twigs, leaves, etc. from falling into the gear train. But the guards are mounted as on a hinge, and can be raised to gain access to the gear train. 120

There are a number of advantageous fea- 125

tures in the sorter. There is quite a demand for devices of this kind in apple raising territories, but it is often the case that known sorters are of a sufficiently complicated nature to make the price rather higher. This sorter is cheaply constructed of material that can be had in almost any shop. But the cheapness of construction in no way makes for a sacrifice in strength because the sorter is very sturdy and durable when completed.

The location of the cull chute 61 makes for convenience in the use of the sorter. The operatives will always be required to face their work, and it is a matter of the least effort to pick defective fruit from the grading rolls 22 and toss it into the centrally located cull chute. Much of the work of separation is accomplished by the eliminating device. Only apples of a certain size will be discharged upon the grading rolls and all that the operatives have to do is to look for partially decayed or otherwise defective apples.

The repeated reference to apples is not to be regarded as a limitation upon the use of the sorter. Things other than apples can be assorted. For instance the sorter might be used for peaches or oranges.

Some stress is to be placed on the importance of the cull chute 61. This is intended to be of practically unlimited capacity. Sometimes the apples run as high as 75% culls when a poor job of spraying has been done. Often the percentage of culls runs as low as 10%. When the percentage of culls runs high the sorter must have ample provision for the disposal thereof. The chute is the thing that will serve the purpose. A conveyor belt would not do because a belt of the necessary and desired size would be prohibitively large and cumbersome.

While the construction and arrangement of the improved sorter is that of a generally preferred form, obviously modifications and changes may be made without departing from the spirit of the invention or the scope of the claims.

We claim:

1. A sorter comprising a perforated belt upon which apples are to be loaded for a separation of apples large enough to lodge in the perforations from apples small enough to pass through the perforations, means to receive the small apples passing through, and means to both support the receiving means and stand in the way of protruding parts of the lodged apples to push said apples out of the perforations.

2. A sorter comprising an endless perforated belt upon one side of which apples are to be loaded, a trough to receive small apples dropping through the perforations, and means extending crosswise of the belt to both support the trough and act as an elevator for

dislodging the apples sticking in the perforations.

3. A sorter comprising an endless perforated belt upon one side of which apples are to be loaded, rolls over which the belt is trained, guide means to sustain one side of the belt leaving the other side to sag, a trough situated between the sides of the belt, being accommodated by the sag to receive small apples dropping through the perforations, and means extending transversely of the guide means and in the direction of an adjoining one of the rolls serving the double purpose of supporting the trough and elevating apples sticking in the perforations before said apples can reach such roll.
